DOOR LOCK

Walter R. Schrage, Burlingame, Calif., assignor
to Schrage Lock Company, San Francisco,
Calif., a corporation of California

Application April 2, 1941, Serial No. 386,478

8 Claims. (Cl. 70—143)

This invention relates to door locks of the type disclosed in my copending application entitled "Door lock," filed April 2, 1941, Serial No. 386,479 and especially to a lock of this character which employs a single spindle.

In the door lock disclosed in my copending application above referred to, a latch bolt is disclosed which is adapted to assume two positions: first, a normal half-projected position; and secondly, a fully projected position. The latch bolt is attached to a retractor plate, and this is actuated by rollback members formed on an inner and an outer spindle. Within these spindles is mounted an actuator which controls the position of the latch bolt, and also a dogging member whereby the outer spindle is dogged against rotation when the latch bolt is fully projected. This actuator is controlled by a key mechanism disposed in the outer spindle, and said mechanism is rotatable. It is also controlled by a longitudinally movable member manually operated by a pushbutton mounted in the inner spindle.

The object of the present invention is to provide a door lock having a latch bolt which is adapted to assume two positions, first a normal half-projected position, and second a fully projected position; to provide a door lock in which the latch bolt is attached to a retractor plate, which in this instance is actuated by a rollback member formed on a single spindle; to provide an actuator within the spindle which controls the position of the latch bolt; to provide key-actuated means in the outer end of the single spindle for rotating said member, and manually operated means in the inner end of the spindle which is also rotatable to control the position of the actuator; to provide means on the latch bolt for dogging the single spindle against rotation when the latch bolt assumes its fully projected position; to provide means whereby the key actuated means or the manually actuated member in the inner end of the spindle will undog the spindle and restore the latch bolt to its normal projected position; to provide a latch bolt which when fully extended cannot be depressed by engagement with the striker plate; and further, to provide a spring-actuated auxiliary plate which remains in constant engagement with the rollback member of the single spindle to secure this and a pair of knobs secured thereto against free rotation.

The invention is shown by way of illustration in the accompanying drawings, in which

Fig. 1 is a horizontal longitudinal section taken on line I—I of Fig. 2, said view showing the latch bolt in normal projected position, and the single

spindle and the knobs secured thereto in undogged position;

Fig. 2 is a vertical longitudinal section taken on line II—II of Fig. 1;

Fig. 3 is a section similar to Fig. 1, showing the latch bolt in its fully projected position, and the single spindle and knobs in dogged position;

Fig. 4 is a perspective view of the retractor plate and the latch bolt carried thereby;

Fig. 5 is a perspective view of the auxiliary plate;

Fig. 6 is a perspective view of the single spindle;

Fig. 7 is a perspective view of the actuator which controls the position of the latch bolt and the dogging member; and

Fig. 8 is a perspective view of the key-actuated tumbler cylinder.

Referring to the drawings, and particularly to Figs. 1 to 3, A indicates a portion of a door, to which is suitably secured a lock housing consisting of two side plates 2 and 3 which are joined at their outer ends by a face plate 4. Secured between the plates 2 and 3 of the lock housing is a U-shaped frame consisting of upper and lower horizontally extending arms 5 and 6 which are connected at their rear ends to an end member 7. The forward ends are provided with right-angularly bent lugs 8—8, and they are secured to the face plate 4 by rivets, countersunk screws or the like, such as indicated at 9. The latch bolt proper is indicated at 10. It extends through an opening 11 formed in the face plate, and is guided thereby. The latch bolt is secured to a retractor plate generally indicated at B (see Figs. 1, 2 and 4). The plate is rectangular in shape, and has an elongated opening 12 formed therein, through which a spindle hereinafter to be referred to extends. The plate is provided with two guide lugs 13—13 which extend into slots 14—14 formed in the horizontal arms 5 and 6 of the U-shaped frame. These lugs guide the rear end of the retractor plate, while the latch bolt 10 guides the forward end. The retractor plate is otherwise provided with a head member 15, on which is formed a dog 16. This head is cut away or notched as at 18, and it is provided with two shoulders 19—19, the purpose of which will hereinafter be described.

An auxiliary plate is also employed, and this is generally indicated at C (see Figs. 1, 2 and 5). It is rectangular in shape, and is also provided with lugs such as shown at 13^a which guide it in the slots 14. The plate C is further provided with a central opening such as indicated at 12^a,

and it has a notch and a pair of shoulders 15b hereinafter to be referred to.

Formed on the side plates 2 and 3 of the main lock housing are outwardly extending bearing hubs 20 and 21, in which is journaled a spindle generally indicated at D. This spindle is best shown in Figs. 1 and 6. A central portion, indicated at 23, is enlarged in diameter, while the inner and outer ends are reduced in diameter as shown at 24. The central enlarged portion is cross-slotted as shown at 25, and a rollback member 26 is thus formed. The opposite sides of the cross-slot are notched on opposite sides, as shown at 27, and one or the other of these notches is provided for the reception of the dogging member 16. Inasmuch as there is only one dog 16 formed on the retractor plate B, only one of the notches 27 would be required, but two are preferably employed, as this allows for both right-hand and left-hand installations. 20

A pair of knobs 30 and 31 are secured on the opposite ends of the spindle. The knob 30 will hereinafter be referred to as the outer knob, and the knob 31 as the inner knob. Insertable through the inner knob and the spindle is a 25 bar 32, which is circular in cross section and snugly fits the interior of the spindle, which is tubular. A collar 33 is formed on the outer end of said bar, and engages the end of the spindle. This collar is overlaid by an annular shoulder 34 formed on the knob, and the bar is thus secured against endwise movement within the spindle, but it is free to rotate, and means in the form of a turnpiece 35 is formed on the outer end of the bar and projects beyond the 30 face of the knob 31 to permit it to be grasped so as to rotate the bar 32. The bar 32 is best shown in Figs. 1 and 7. Adjacent its inner end is formed a flat portion 36 which will hereinafter be referred to as an actuator. Beyond 40 that is a cylindrical extension 37, and on the end thereof is formed a lug 38.

Extending through the outer knob 30 and into the tubular spindle is a key-actuated tumbler cylinder 39. The spindle proper functions as a 45 housing for the cylinder, and the tumblers 40 normally project into a slot 41 formed in the spindle, and thus secure the cylinder against rotation. However, by inserting a key the tumblers 40 are retracted, and the cylinder is then 50 free to rotate; when it is rotated, a lug 42 formed on the inner end thereof engages the lug 38 of the actuator, and rotation is thereby imparted to the actuator by the key-actuated cylinder. The key cylinder has a collar 45 formed at its 55 outer end, and this is overlaid by an annular shoulder 46 formed on the knob. The key cylinder is thus secured against endwise movement, but it is free to rotate a half revolution within the spindle, as will hereinafter be described. 60

The normal position of the mechanism is that shown in Fig. 1. In this position the latch bolt 10 is half-projected, and it is maintained in this position by means of the actuator, or in other words the flattened bar 36. This bar when in 65 horizontal position, as shown in Figs. 1 and 2, engages the inner end of the notch 18 formed in the retractor plate, and this holds the retractor plate, together with the latch bolt, secured thereto, in a partially retracted position, 70 where the dog 16 is maintained out of engagement with the notch 27 formed in the spindle, and the shoulders 19 out of engagement with the rollback member 26. In this position the spindle is undogged and may be rotated by either 75

knob, and when it is rotated by either knob the rollback member 26 (see Fig. 2) will engage one or another of the shoulders 15b of the auxiliary plate C and force it in a rearward direction, and when said shoulders align with the shoulders 19 formed on the main retractor plate, both the retractor plate and the auxiliary plate will move rearwardly in unison, and the latch bolt 10 will be fully retracted. Conversely, by releasing the spindle, by letting go of whichever knob has been grasped, the springs indicated at 50 and 51 will return both plates to normal position and thereby reverse the rotation of the spindle and the knobs, and the bolt will be returned to normal or half-projected position, as forward movement of the retractor plate will be limited by the horizontal position of the bar or actuator 36.

If a person is in the room and desires to lock the door against intruders, it is only necessary for that person to grasp the turnpiece and rotate the bar 32 and the bar 36 until the latter assumes a vertical position. In this position, the retractor plate can advance until the shoulders 19—19 engage the rollback member 26, and when they do so, the bolt 10 will assume its fully projected position, or that shown in Fig. 3. At the same time the dogging lug 16 will enter the notch 27 of the spindle, and the spindle, together with both the inner and the outer knobs, will be dogged against rotation. Thus the door is locked against any intruder, but it may be opened from the outside by a person having the proper key, as the insertion of a key will retract the tumblers 40 and permit rotation of the cylinder 39, and when it is rotated the lug 42 will engage the lug 38 on the inner end of the bar 32 and rotate it until the actuator returns to the horizontal position shown in Fig. 2. In this position the retractor plate will be forced rearwardly a sufficient distance to retract the dogging lug from the notch 27 and to retract the bolt 10 to its normal half-projected position. In this position, either the outer or the inner knob may be rotated to rotate the spindle and the rollback member to fully retract the latch bolt and thereby permit opening of the door.

The position of the latch bolt is thus controlled by the actuator 36, as when the actuator assumes a horizontal position the bolt will be half projected, and when it assumes a vertical position the bolt is fully projected, and the spindle will at the same time be dogged, as the dog 16 will enter the notch 27.

The spindle may be dogged either by key actuation or by rotation of the turnpiece 35; also, it is impossible for a person to lock the door from the interior and then to go out and close the door without the use of a key, for the simple reason that if the bar 32 is rotated by means of the turnpiece 35 to move the actuator 36 to a vertical position, the dog will assume dogging position and the latch bolt its fully projected position. In this position it is impossible to close the door, as the fully projected latch bolt will extend too far to be depressed by the striker plate, thus making it impossible to close the door. The bolt 32 will therefore have to be re-rotated to return the bar 36 to horizontal position before the door can be closed and after it has been closed it can be locked by a key only.

Earlier in the specification it was stated that the retractor plate B had an opening 12 formed therein, and that the auxiliary plate C had a sim-

ilar opening 12a. These openings are provided merely to permit the spindle to pass through the plates and to permit retraction of the plates. The auxiliary plate C performs only one function, and if it were not for that function it could be entirely discarded. That function is to hold the spindle and knobs against free rotation. That is, the normal position assumed by the retractor plate is that shown in Figs. 1 and 2; in this position it will be noted that the shoulders 19—19 of the retractor plate assume the dotted line position shown in Fig. 2. In other words, they are spaced away from and out of engagement with the rollback member 26. If it were not for the auxiliary plate, the spindle and the knobs would be free to rotate without any resistance until the rollback member engaged the shoulders 19—19. Such free rotation would obviously be undesirable. It is for this reason that the auxiliary plate is employed. Its shoulders 15b are at all times in engagement with the face 26 of the rollback member, and as the spring 51 is continuously exerting its pressure on the auxiliary plate, rotation of the spindle and the knobs is resisted by the spring 51. Thus the spindle and knobs are held against free rotation, but they are nevertheless rotatable in the usual manner, that is, by grasping one knob or the other and rotating it against the pressure of the spring 51, and finally against the pressure of the springs 50.

In the present drawings set screws are shown as securing the knobs to the spindle, but any other suitable means may be employed, and while this and other features of the invention have been more or less specifically described and illustrated, I wish it understood that changes may be resorted to within the scope of the appended claims, and similarly that the materials and finish of the several parts employed may be such as the experience of the manufacturer or varying conditions may dictate.

Having thus described my invention, what I claim and desire to secure by Letters Patent is

1. In a lock, a latch bolt adapted to assume a partially or a fully projected position, a spindle having means for retracting the latch bolt from the partially projected position, a movable member within the spindle having one surface engaging and retaining the latch bolt in the partially projected position and another surface adapted to engage and permit full projection of the latch bolt, and manually operated means for moving the member to present either surface for engagement with the latch bolt, so as to maintain the latch bolt in either the partially or the fully projected position.

2. In a lock, a latch bolt adapted to assume a partially or a fully projected position, a spindle having means for retracting the latch bolt from the partially projected position, a movable member within the spindle having one surface engaging and retaining the latch bolt in the partially projected position and another surface adapted to engage and permit full projection of the latch bolt, and key actuated means for moving said member to present either surface for engagement with the latch bolt, so as to maintain the latch bolt in the partially or the fully projected position.

3. In a lock, a retractor plate, a latch bolt secured thereto, said retractor plate adapted to assume two positions, one in which the latch bolt is partially projected and a second position in which the latch bolt is fully projected, a single

tubular spindle journaled in the lock, a rollback member on said spindle engageable with the retractor plate and adapted to retract the latch bolt from the partially projected position, a dog on the retractor plate engageable with the spindle and dogging the spindle against rotation when the latch bolt is fully projected, a rotatable member within the spindle controlling the position of the retractor plate and the dog and latch bolt carried thereby, and rotatable means at each end of the spindle for rotating the rotatable member to control the position of the latch bolt and the dog.

4. In a lock, a retractor plate, a latch bolt secured thereto, said retractor plate adapted to assume two positions, one in which the latch bolt is partially projected and a second position in which the latch bolt is fully projected, a single tubular spindle journaled in the lock, a rollback member on said spindle engageable with the retractor plate and adapted to retract the latch bolt from the partially projected position, a dog on the retractor plate engageable with the spindle and dogging the spindle against rotation when the latch bolt is fully projected, a rotatable member within the spindle controlling the position of the retractor plate and the dog and latch bolt carried thereby, key actuated means at one end of the spindle, and manually actuated means at the opposite end of the spindle, for rotating the rotatable member so as to control the position of the retractor plate and thereby the position of the latch bolt and the dog.

5. In a lock of the character described, a tubular spindle having a rollback member formed thereon, a retractor plate having a latch bolt secured thereto, said rollback member being engageable with the retractor plate to impart a retracting movement to the plate and the latch bolt when the spindle is rotated, said retractor plate and the latch bolt adapted to assume one position where the latch bolt is fully projected and the retractor plate is in engagement with the rollback member, and a second position where the retractor plate is held out of engagement with the rollback member and the latch bolt is partially retracted, a member within the spindle and engageable with the retractor plate to maintain it and the latch bolt in one position or the other, and an auxiliary spring-actuated plate engageable with the rollback member at all times and resisting rotation of the rollback member and spindle.

6. In a lock of the character described, a tubular spindle having a rollback member formed thereon, a retractor plate having a latch bolt secured thereto, said rollback member being engageable with the retractor plate to impart a retracting movement to the plate and the latch bolt when the spindle is rotated, said retractor plate and the latch bolt adapted to assume one position where the latch bolt is fully projected and the retractor plate is in engagement with the rollback member, and a second position where the retractor plate is held out of engagement with the rollback member and the latch bolt is partially retracted, and a yieldable member resisting free rotation of the spindle and rollback member at all times.

7. In a lock of the character described, tubular spindle having a rollback member formed thereon, a retractor plate having a latch bolt secured thereto, said rollback member being engageable with the retractor plate to impart a retracting movement to the plate and the latch

bolt when the spindle is rotated, said retractor plate and the latch bolt adapted to assume one position where the latch bolt is fully projected and the retractor plate is in engagement with the rollback member and a second position where the retractor plate is held out of engagement with the rollback member and the latch bolt is partially retracted, a knob secured on the spindle, and an auxiliary spring-actuated plate engaging the rollback member at all times and resisting free rotation of the spindle, said plate permitting rotation of the spindle when the knob is grasped and rotated.

8. In a lock of the character described, a tubular spindle having a rollback member formed thereon, a retractor plate having a latch bolt secured thereto, said rollback member being engageable with the retractor plate to impart a retracting movement to the plate and the latch

bolt when the spindle is rotated, said retractor plate and the latch bolt adapted to assume one position where the latch bolt is fully projected and the retractor plate is in engagement with the rollback member, and a second position where the retractor plate is held out of engagement with the rollback member and the latch bolt is partially retracted, a member within the spindle and engageable with the retractor plate to maintain it and the latch bolt in one position or the other, means at one end of the spindle for actuating the member within the spindle and thereby controlling the position of the retractor plate and the latch bolt, a yieldable member resisting free rotation of the spindle and rollback member at all times, and a knob on the spindle, said yieldable member permitting rotation of the spindle when the knob is manually rotated.

WALTER R. SCHLAGE.
